CHEST

Walter Ziegler, Forest Park, Ill., assignor to Ed. Roos Company, a corporation of Illinois

Application December 12, 1934, Serial No. 757,175

4 Claims. (Cl. 312—189)

This invention relates to household furniture, and, more particularly, to clothes chests and the like.

One of the objects of the invention is the provision of a chest having a novel arrangement of compartments movably connected together.

Another object of the invention is the provision of new and improved means for movably connecting an upper compartment to a lower receptacle or main body of the chest that is so constructed and arranged that the upper compartment which forms a closure for the chest will be prevented from projecting rearwardly of the plane of the back of the chest during the opening and closing operations.

A further object of the invention is the provision of a new and improved hinge mechanism for connecting a closure to a receptacle in such a manner that the weight of the closure will be partially counterbalanced during the opening and closing operations.

A still further object of the invention is the provision of new and improved hinge mechanism for the closure of a chest whereby the closure will be seated on the lower compartment when in opened position and will be automatically held in open position, and which will be limited in its rearward movement by such mechanism.

A further object of the invention is the provision of a new and improved chest and associated parts that are inexpensive to manufacture, easily assembled, efficient in use and which will be unobtrusive and pleasing in appearance.

Other and further objects and advantages of the invention will appear from the following description taken in connection with the following drawing, in which—

Fig. 1 is a perspective view of the chest with parts broken away and showing the closure in open position;

Fig. 2 is a perspective view of the hinge mechanism;

Fig. 3 is a cross section of the chest showing the closure in closed position;

Fig. 4 is a similar view but showing the closure in open position; and

Fig. 5 is a vertical section through a portion of the chest showing the locking mechanisms.

Referring now to the drawing, the reference character 10 designates generally the chest which comprises the lower section or compartment 11 and the upper section, compartment or closure 12 provided with a lid 13. The lower compartment 11 may be of the usual or any well-known construction and is preferably, though not neces-

sarily, provided with feet, legs or supports 14 and 15.

The upper section or closure comprises a receptacle 16 which corresponds in length and width to the lower receptacle and constitutes a closure therefor. The lid 13 forms a closure for the receptacle 16 and is hinged thereto in any suitable manner, as by means of the hinges 17.

The upper section 12 is movably connected to the lower section 11 by a mechanism that will permit the closure to be opened without projecting the same rearwardly beyond the plane of the rear wall of the chest during the opening and closing operations. By means of such mechanism, the chest may be pushed back against the wall of the room containing the same, and the closure opened without moving the chest away from the wall. Furthermore, the closure 12 is in the form of a receptacle which may be of a substantial depth for receiving clothing, bedding or the like, and when the upper receptacle or closure is filled, the weight thereof may be considerable, and, for that reason, it is desirable that means be provided for equalizing or counterbalancing the weight thereof, while same is being opened. Any suitable mechanism may be employed for performing these functions. In the form of construction selected to illustrate one embodiment of the invention, and which is by way of example only, a plurality of links are employed for this purpose.

As shown, two links 18 and 19 of substantially the same length are employed for movably connecting the two sections together. These links are preferably, though not necessarily, duplicates of each other, whereby their assembly is materially facilitated. The lower ends of these links are pivotally connected to the lower section or compartment 11 and the upper ends of same are pivotally connected to the upper compartment or closure 12.

Any suitable means may be employed for pivotally connecting the links to the sections. In the form of construction shown, the lower ends of the links are connected to a pivot bar or plate 21, the central portion of which is rigidly connected to the end wall of the lower compartment, as by means of the screws 22 located at points below the upper edge of said end wall.

The ends of the bar are offset inwardly to which the links 18 and 19 are pivotally or hingedly connected, as by means of the pivots 23 and 24. The upper ends of the links 18 and 19 are pivotally connected to a hinge plate 25 secured to the bottom wall of the upper receptacle 16.

or compartment 12 at points inwardly of the rear edge thereof. This plate is preferably angular in cross section, one flange engaging the bottom of the receptacle and secured thereto, 5 as by means of the screws 26. The other flange 20 extends outwardly and has pivotal connections with the upper ends of the links 18 and 19, as clearly shown in Fig. 4 of the drawing. The bar 21 is arranged angularly across the end wall 10 of the lower closure with the pivot 23 below the pivot 24, as shown in Fig. 4.

The plate 25 is much shorter than the bar 21 and due to these dimensions and the arrangement of the parts, the closure is caused to move 15 inwardly by these links when the same is elevated from the front so that no part of the closure will project rearwardly of the rear wall 21 of the lower compartment during the opening and closing operations.

20 It will also be seen that since the hinge plate 25 is secured to the bottom of the upper closure that when the closure is in open position, as shown in Fig. 4, its center of gravity has passed 25 dead center and the closure will rest on the upper edge of the lower compartment for holding the same in open position, as shown in Fig. 4. Furthermore, due to this arrangement of the plate 25, the weight of the upper compartment will be largely borne by the links 18 and 19 during 30 a major portion of the opening and closing of this compartment, thereby facilitating these operations.

The hinge mechanism may be assembled as a unit and is ready to be attached in position by applying the screws. The links are both attached to the same side of the flange 20 and consequently when the upper compartment of the chest is opened, one of these links may, in certain constructions, engage the other, thereby 40 limiting the opening movement of the compartment.

Since the links may be made from light material, it is desirable that means be provided for guiding the same and for preventing the 45 links from bending laterally. Any suitable mechanism may be employed for this purpose. As shown, guides or keepers 28 are provided. These guides each comprise metal links or strips provided with a central offset portion 30 for extending about the links 18 and 19 and have their 50 ends provided with openings for receiving screws for attaching the guides to the end walls of the lower compartment, as clearly shown in Figs. 3 and 4 of the drawing. These guides permit the links to move transversely of the chest during 55 the opening and closing movement of the closure, and at the same time will prevent lateral movement of said links.

Appropriate means are provided for latching 60 the lid 13 and the closure 12 in lowered positions. These latching means are preferably in the form of push buttons, and since they are similar, only one need be described. Each of the latch members comprises a shank portion having an upwardly extending latch or catch portion 31 which is adapted to engage in an opening 32 in an angular keeper 33 rigidly secured in a suitable recess 34 in the side walls of the compartment.

70 The shank portion 29 extends forwardly and terminates in a push button 35 which is slightly enlarged to form a shoulder for engaging a spring 36 which normally holds the button 35 extended for causing the latch 31 to engage in the opening 75 32 for locking the lid or upper closure in

lowered position. Preferably, a finger device or handle 37 is provided on the upper closure between the two latches so that in opening either the lid or the upper compartment or closure, the operator may grasp the handle 37, and with 5 the thumb or one of the fingers of the same hand may release one or the other of the latches by pushing the corresponding button, as desired.

By making the hinge mechanism of comparatively thin links, the greater portion of this mechanism will be concealed by a liner 40 of fibrous material that may be used for lining the bottom and side walls of the lower compartment. This lining material when in position over the 15 links will prevent the same from contacting the clothes and wearing, cutting or tearing said garments during the opening and closing of the chest.

I claim as my invention:—

1. A chest comprising a lower compartment, a closure for said lower compartment, and means for hingedly connecting said closure and said compartment together, said means comprising a pair of links of substantially the same length, an attaching plate secured to the inner surface of an end wall of said lower compartment with the forward end of the plate spaced above the level of the rear end thereof, an angle plate having one flange connected to the lower surface of said closure within said chest and adjacent to the rear edge thereof, said links being pivoted to the respective ends of the attaching plate and angle plate for movement in the same plane, and a guide strip extending over intermediate portions 35 of said links for guiding the same and for preventing lateral bending thereof.

2. A chest comprising a lower compartment, a closure for said lower compartment, and means for hingedly connecting said closure and said compartment together so that the closure may be raised to vertical position adjacent to and forwardly of the rear edge of the chest, said means comprising a pair of links of substantially equal length, means for pivotally connecting the lower 45 ends of said links in substantially the same plane on an end wall of the lower compartment at vertically and laterally spaced points, the point nearer the rear edge of the chest being below the level of the point more remote from said rear edge, and having their upper ends pivotally connected to said closure.

3. A chest comprising a lower compartment, a closure for said lower compartment, and means for hingedly connecting said closure and said compartment together so that the closure may be raised to vertical position adjacent to and forwardly of the rear edge of the chest, said means comprising a plate, having a pair of laterally and vertically spaced pivots thereon, mounted on an 60 end wall of the lower compartment and in a plane parallel thereto, a pair of pivots carried by the closure near the rear edge thereof and in the plane of the first named pivots, and a pair of links of substantially equal length each connected at 65 its extreme ends to one of each of said pairs of pivots, whereby the links are mounted for movement in substantially the same plane and whereby the paths of their movement do not intersect when the closure is raised or lowered with relation 70 to the lower compartment.

4. A chest comprising a lower compartment, a closure for said lower compartment, and means for hingedly connecting said closure and said compartment together so that the closure may be 75

5 raised to vertical position adjacent to and forwardly of the rear edge of the chest, said means comprising a plate secured to the inner side of an end wall of said lower compartment, a pair of laterally and vertically spaced pivots projecting from the interior surface of said plate, a second plate having a pair of pivots carried on the under surface of the closure near the rear edge thereof and in the plane of the first named pivots, and a

pair of links of substantially equal length each connected at its opposite ends to one of each of said pairs of pivots, whereby the links are mounted for movement in substantially the same plane and whereby the paths of their movement do not intersect when the closure is raised or lowered with relation to the lower compartment. 5

WALTER ZIEGLER.
